ELECTRICAL SCOREBOARD FOR GOLF PRACTICE APPARATUS

William J. Graham, Johnstown, N.Y., assignor to
J. Myer Schine, Gloversville, N.Y.

Filed Dec. 7, 1964, Ser. No. 82,930

Term of patent 14 years

(Cl. D34—5)

The single figure is a perspective view of an electrical scoreboard for golf practice apparatus showing my new design.

The back, bottom, and opposite side of the scoreboard not shown are plain.

The characteristic features of the design reside in the combination on the face of an elongated rectangular scoreboard cabinet of a horizontally extending contrasting stripe, terminating short of opposite ends of the face, having a portion at one end extending vertically above and below the horizontal stripe and a plurality of vertically directed portions at longitudinally spaced intervals, a plurality of protruding illuminating elements disposed within and throughout the length of the horizontal stripe and the vertically extending and directed portions, a pair of centrally disposed contrasting markings above the horizontal stripe with illuminating elements protruding therefrom, and oppositely directed contrasting arrow designs spaced above said horizontal stripe and on opposite sides of said centrally disposed markings with a plurality of illuminating elements protruding from each arrow design, all as shown.

I claim:

The ornamental design for an electrical scoreboard for golf practice apparatus, as shown and described.
